SEMIAUTOMATIC TELEGRAPHIC SENDING
MACHINE

Horace G. Martin, Brooklyn, N. Y.

Application April 4, 1940, Serial No. 327,757

15 Claims. (Cl. 178—82)

The present invention relates to improvements in semiautomatic telegraphic sending machines of the type disclosed in the United States Patent #1,445,226 generally known as the Martin machines, and more particularly to the construction of the contact making key operated lever mechanism and its supporting means.

As is well known, machines of this type are generally individually owned by the operators who carry them from place to place to be plugged in wherever necessary for operation. As hitherto constructed the manufacture of these machines is somewhat expensive, partly due to numerous parts requiring finishing and polishing.

My invention, therefore, has for its main object to greatly simplify the construction of said machine, so as to reduce the number of parts and also save material, thereby rendering the machines less expensive and more compact and, therefore, more convenient to be transported from place to place than the hitherto used machines.

In the accompanying drawing which constitutes part of this specification and in which similar reference characters denote corresponding parts,

Figure 1 is a top plan view of the machine;

Figure 2 is an enlarged longitudinal section thereof, along line 2—2 of Figure 1;

Figure 3 is a similar section to Figure 2 of a slightly modified construction;

Figure 4 is a top plan view of another modification and

Figure 5 is a sectional elevation thereof.

Referring to the drawing more in detail and first to the structure shown in Figures 1 and 2, 10 denotes the metal base of the machine which is provided with rubber feet or rests 11. Fixedly mounted on or formed integrally with said base is a boss 12 which serves as a support for the operating mechanism. This mechanism comprises two levers extending longitudinally of the base and adapted to bear upon one another in a vertically superposed position. Lever 13 has attached to its rear end the insulated hand and thumb pieces 15 and 16 and an electric contact point 17 which in cooperation with an adjustable stationary contact piece 18 provided in the post 19 serves for the transmission of "dash" signals. The forward end of said lever is formed to a circular disk 13a. The second lever 14 has attached to its forward end by a leaf spring 20 the weight controlled vibratory rod 21 carrying the resiliently supported contact point 22 which in well-known manner through the vibration of the rod 21 cooperates with the stationary adjustable

contact piece 23 provided in the post 24 to produce the "dot" signals. 30 and 31 are adjustable stops arranged at both sides of the lever 14 to regulate the extent of movement of the lever 14.

Like lever 13, this lever 14 is formed at its rear part to a circular disk 14a. These two disk shaped portions 13a and 14a are adapted to bear upon one another and to be suitably centered on the boss 12, as by a bolt or pin 25, which projects through central bores of said disks and through a vertical bore provided in the boss 12. The lower end of said bolt or pin 25 projects into a recess 10a in the bottom of the base 10 and may be screw threaded to receive a nut 26. The upper end of the bolt may be formed with a small head 25a to bear on the upper face of disk 14a of the lever 14. Projecting from the rear edge of the disk shaped portion 14a of the lever 14 substantially parallel to but slightly spaced in lateral direction from the lever 13 is an abutment or tail member 14b. A set screw 27 projecting through a bore in the said member 14b and fixed to lever 13 carries a coil spring 28 which bears at one end against a nut 29 working on said screw and at the other end against said extension 14b. This spring is adapted to normally hold lever 13 against the rear extension 14b of lever 14.

A suitable anti-friction bearing is provided between the disks 13a and 14a of the levers 13 and 14. According to the modification shown in Figure 2, this bearing comprises a concentric annular rounded bead 13c provided on one of said disks, as 13a, and adapted to rotatively engage a correspondingly shaped groove 14c provided in the opposite disk, as 14a.

The operation of the machine is the same as in the patent hereinbefore referred to. Normally the rear portion of the lever 13 through the tension of the spring 28 is held in contact with the rear extension 14b of the lever 14. For sending a "dash" message the operator by grasping the hand and thumb pieces 15 and 16 swings the lever 13 on its vertical axis around the bolt 25 until its contact point 17 is brought into contact with the stationary contact point 18. During this movement the lever 14 remains stationary resting against the stop 30. For sending "dot" messages the lever 13 is swung in the opposite direction to act against the abutment 14b of the lever 14 thereby swinging the latter on its vertical axis until it strikes the stop 31. As a result thereof the weight regulated rod 21 with its resilient contact point 22 is set into vibratory motion repeatedly making and breaking the con-

- tact between itself and the stationary contact 23, the number of "dot" signals to be sent depending upon the length of time the lever 14 is kept in contact with the stop 31. Upon the release of the 5 hand pieces 15, 16 the spring 32 mounted around the stop 31 will return the parts to the normal position and the forward end of the rod 21 will be brought in contact with a dampening roller 34 to stop further vibrations.
- 10 In the modification shown in Figure 3 instead of the annular bead and groove shown in Figure 2, a suitable ball bearing 33 is used. As shown in this modification annular beads and grooves may also be provided between the bearing surfaces of 15 the head 25b of the bolt and upper face of the disk 14' of lever 14 and between the boss or block 12a and the lower face of disk 13' of lever 13, the same serving to further reduce friction between these parts, when the levers are moved. The 20 head of the bolt as well as the bearing surface of the boss, in practice, are of such small diameter that friction between these parts is negligible and means for reducing friction for these parts can be dispensed with, as in Figure 2. However, 25 the bearing surface between the disks 13a, 14a are made comparatively larger in order to steady them in their superposed position and, therefore, suitable anti-friction means, as those shown in Figures 2 and 3 are indispensable.
- 30 By arranging the levers in superposed position many parts in the old structures are eliminated, thereby considerably simplifying the manufacture and reducing the cost thereof.
- A still further simplification of the machine is 35 obtained by the modification shown in Figures 4 and 5. Here the rear lever 13 is arranged in longitudinal extension of and yieldingly connected to the lever 14 as by a short leaf spring 35. The lever 14 may be provided with the disk shaped 40 portion, as in the modification hereinbefore described, and there may be either the ball bearing 33 or other friction reducing means between said disk and boss 12. The leaf spring 35 has one end suitably fixed in a slit of the rear end of the lever 45 14 or its disk shaped portion and its other end in a slit of lever 13 as shown in Figure 4.
- The spring 29 normally hold the lever 13 in contact with the tail or abutment 14b of the lever 14 against the tension of the leaf spring 35.
- 50 The leaf spring 35 permits the movement of lever 13 in two directions, in one direction to close contacts 17, 18 to produce "dash" signals without affecting the lever 14, and in the opposite to act on lever 14 for producing "dot" signals.
- 55 What I claim:
1. In a semiautomatic telegraphic sending machine of the character described, the combination with a base, of a boss projecting upwardly from said base, a contact operating lever mechanism 60 comprising a handle operated contact lever, a vibratory contact carrying lever actuated by said handle lever, both levers being formed with relatively flat surfaces rotatively bearing upon one another and on said boss and friction reducing 65 means directly between the opposite faces of said surfaces.
  2. In a semiautomatic telegraphic sending machine of the character described, according to claim 1, in which said flat surfaces are formed by disk shaped portions between them.
  3. In a semiautomatic telegraphic sending machine of the character described, according to claim 1, in which said flat surfaces are formed by disk shaped portions and have a ball bearing 70 located directly between them.

4. In a semiautomatic telegraphic sending machine of the character described, according to claim 1, in which said flat surfaces are formed by disk shaped portions and in which a friction reducing means is provided between said disk shaped portions and a friction reducing means between the lower one of said portions and said supporting boss. 5

5. In a semiautomatic telegraphic sending machine of the character described, according to claim 1, in which said flat surfaces are formed by disk shaped portions rotatively supported on said boss and in which a centering pin fixed to said base projects through said boss and said disk shaped portions. 15

6. In a telegraphic sending machine, a support, handle operated contact lever, and a vibratory contact lever, both said levers having relatively broad disk shaped flat portions adapted to rotatively bear upon one another and to be centered 20 on said support.

7. In a semiautomatic telegraphic sending machine of the character described, the combination of a base, an upright stationary support on said base, contact levers, each formed with a flange, 25 both said flanges being rotatively mounted in superposed position on said stationary support and friction reducing means directly between the opposite faces of said flanges.

8. In a semiautomatic telegraphic sending machine of the character described, the combination of a base, a stationary support thereon, contact levers, each formed with a flange, both said flanges being rotatively mounted in superposed position on said stationary support, friction reducing means directly between the opposite faces of 35 said flanges and friction reducing means directly between the lower one of said flanges and said support.

9. In a semiautomatic telegraphic sending machine of the character described, the combination of a support, a contact operating mechanism comprising a non-vibratory manually operated lever, a second lever adapted to be actuated by said first-named lever, one of said levers being 45 formed with a flange rotatively mounted on said support, a resilient joint between said flange and said second lever and means whereby said second-named lever will transmit motion to said first-named lever when swung in a certain 50 direction. 40

10. In a semiautomatic telegraphic sending machine, according to claim 9, in which said last-named means include an abutment projecting from the edge of said flange and against which 55 said second lever acts to transmit motion to said first-named lever.

11. In a semiautomatic telegraphic sending machine of the character described, the combination of a stationary upright support, a stationary upright pin in said support, contact levers having flanges rotatively mounted on said support and centered on said stationary pin and friction reducing means directly between the opposite faces of said flanges. 60 65

12. In a semiautomatic telegraphic sending machine, according to claim 11 in which the opposite face of each of said flanges is provided with a circular groove, to receive balls and constitute with the latter anti-friction bearings for 70 said levers.

13. In a semiautomatic telegraphic sending machine, according to claim 11, in which one of said flanges is provided with a circular bead and the other with a corresponding groove adapted 75

to rotatively engage said bead and in cooperation therewith to constitute an anti-friction bearing for said levers.

14. In a semiautomatic telegraphic sending machine, an upright support, having a relatively broad bearing surface, vertically superposed contact levers, each formed with a correspondingly broad bearing surface, anti-friction means directly between the opposite faces of the bearing surfaces of said levers and anti-friction means between the bearing surface of said support and the bearing face of the lower lever. 5
15. In a semiautomatic telegraphic sending machine, an upright support having a relatively broad bearing surface, vertically superposed contact levers, each formed with a correspondingly broad bearing surface, anti-friction means directly between the opposite faces of said bearing surfaces of said levers, anti-friction means directly between said bearing surface of said support and said bearing surface of the lower lever and means for centering and tightening said levers on said support. 10
